UNITED STATES PATENT OFFICE

ROY R. STEVENS, OF FOREST HILLS, PENNSYLVANIA, ASSIGNOR TO CARDWELL WESTINGHOUSE COMPANY, A CORPORATION OF DELAWARE

FRICITION DRAFT GEAR

Original application filed January 29, 1930, Serial No. 424,202. Divided and this application filed October 8, 1931. Serial No. 567,578.

The invention relates to friction draft gears for railway cars, and this application is a division of my pending application Serial No. 424,202, filed January 29, 1930, for improvements in friction draft gears.

The object of the invention is to provide improved means for resisting the lighter shocks incident to service by cushioning springs, frictional resistance being brought into action when the forces to be resisted exceed the capacity of the springs.

A preferred embodiment of the invention is hereinafter described, and is illustrated in the accompanying drawing in which

Fig. 1 is a plan section of the device as applied to a car;

Fig. 2 is a sectional view on the line 2—2 of Fig. 1; and

Fig. 3 is a detail section on the line 3—3 of Fig. 1.

A pair of center sills of a railway car are represented at 10, each being provided with a draft lug 11 and a buffing lug 12, according to usual practice. The coupler butt is indicated at 13, and the usual yoke for inclosing the gear at 14. A plate follower 15 engages the draft lugs 11, and a chambered follower 16 engages the buffing lugs 12. The cushioning mechanism reacts between the follower 15 and the rear end of the follower 16.

The mechanism for cushioning the lighter shocks comprises a thrust element 17, seated against the follower 15; a spring seat 18, seated against the inner end of the thrust element, and springs 19, 19, reacting between the spring plate and the rear end of the follower 16. The side walls of the follower 16 may be omitted, as indicated, except at their forward ends, for convenience in assembling.

The friction mechanism for resisting the heavier shocks comprises a central element 20, which may be properly characterized as a strut, and, as shown, is an integral oblong rectangular casting having at its top and bottom ends lugs 21 for fitting within transverse channels 22 in the top and bottom walls of the follower 16, whereby the strut is anchored against longitudinal movement.

While the strut is shown as an integral casting, it may, if desired, be vertically and longi-

tudinally divided without modifying its action. This element is longitudinally chambered to accommodate the stem of the thrust element 17 and permit it to move freely therethrough.

The friction mechanism further comprises wedging friction shoes interposed between the strut 20 and the side walls of the follower 16, and frictionally cooperating with each. These wedging elements comprise the shoes 23, which frictionally engage the strut 20 and have wedging faces cooperating with complementary faces on the shoes 24, which frictionally engage the side walls of the follower 16, or, as shown, wear plates 25 seated thereagainst. A spring seat 26 bears against the inner ends of the shoes 23, and a pair of springs 27 react between this spring seat and the rear end of the follower 16, the spring seat 18 being apertured, as indicated at 28, to permit their free passage.

The shoes 24 are provided with lateral lugs 29 at their inner ends, for overlapping rearwardly facing shoulders associated with the side walls of the follower 16, these shoulders, in the disclosed embodiment of the invention, being the rear ends of the wear plates 25. The forward ends of the shoes 24 are spaced normally from the follower 15, and from lateral extensions 30 at the outer end of the thrust element 17, and consequently the friction elements are not brought into action until the follower 15, and with it the thrust element 17, have advanced a substantial distance, being resisted only by the springs 19.

The inner faces of the side walls of the follower 16, or of the wear plates 25 when the latter are used, flare slightly toward the open end of the follower. The plates 25 are provided at their top and bottom margins with lugs 31 for fitting within the channels 22, and thus anchoring the plates against longitudinal movement. A retaining pin 32 is set vertically through the follower 16, the top and bottom walls thereof being apertured for its reception, this pin passing through a longitudinal slot 33 in the stem or shank of the thrust element 17. The length of this slot is sufficient to provide for maximum movement of the thrust element, and its rearward end, coming

into engagement with the pin 32 upon full release of the gear, prevents the withdrawal of the thrust element.

In assembling the gear the several springs 5 and both of the spring plates are first inserted, and the springs are put under preliminary compression and held by a suitable bar which may be thrust through the openings in the side walls of the follower and engages the 10 front face of the seat 26. The wear plates 25 are now inserted, being tilted laterally until their lugs 31 register with the channels 22. The strut element 20 is now similarly introduced, and to facilitate this action two of its 15 diagonally opposite corners, as 34, may be somewhat rounded. The shoes 23, 24, are now inserted and properly positioned, as is also the thrust element, the pin 32 being now introduced for retaining the latter. The 20 springs are now relieved of their initial compression and the gear is ready for service and is held in assembly for shipment.

In action the springs 19 are first compressed by the relative approach of the two followers. 25 Should the compressive action be sufficient to cause the engagement of the lateral extensions 30 of the thrust element and of the follower 15 with the shoes 24, both sets of shoes are advanced into the follower 19 against the 30 resistance of the springs 27 and the friction, augmented by the wedging engagement of the shoes, between the shoes 23 and the side walls of the strut 20, and the shoes 24 and the side walls of the follower 16, or the wear plates 25. 35 The inward inclination of these side walls or wear plates causes a lateral inward movement of the shoes 24, and consequent accelerated advance of the shoes 23.

Upon release the expansion of the springs 40 19 promptly separates the two followers, the seat 18 being brought into contact with the seat 26 and the springs 19 supplementing the action of the springs 27 to cause the outward movement of the shoes until the lugs 29 are 45 brought into engagement with the shoulders of the follower 16.

I claim as my invention—

1. A draft gear comprising a chambered follower having an open end, the inner faces 50 of the front portions of its side walls being inwardly and backwardly inclined, a thrust element projecting centrally into the follower, spring means resisting the advance of the thrust element, a central longitudinally apertured strut anchored to the follower against relative longitudinal movement and loosely enclosing the shank of the thrust element, co-operating wedging elements interposed between and frictionally engaging each side 55 wall of the strut and the inclined walls of the follower, certain of the wedging elements projecting beyond the open end of the follower but to a less distance than the thrust element, independent spring means resisting the advance of the wedge elements, and an opposed 60

follower for applying pressure successively to the thrust element and the projecting wedge elements.

2. In a draft gear, a chambered follower having the front portions of its side walls inwardly and rearwardly inclined, a pair of permanently spaced parallel walls flanking the longitudinal axis of the follower and anchored against longitudinal movement, a thrust element projecting into the open end of the follower and being freely movable between the named parallel walls, spring means resisting the inward movement of the thrust element, cooperating wedge elements located between each of the parallel walls and a side 70 wall of the follower and having frictional engagement with each, a plate follower for applying compressive forces successively to the thrust element and to certain of the wedging elements, and spring means independently resisting the inward movement of the wedge elements. 75

In testimony whereof I affix my signature.
ROY R. STEVENS.
